REFLECTIVE BICYCLE PEDAL

Hubert Joachim Konzorr, Unna, Westphalia, Germany,
assignor to Union Sils, van de Loo & Co. Kom. Ges.,
Fröndenberg, Germany

Filed Feb. 13, 1973, Ser. No. 332,157

Claims priority, application Germany Aug. 14, 1972

Term of patent 14 years

Int. Cl. D12—11

U.S. Cl. D12—125

Fig. 1

Fig. 2

Fig. 3

Fig. 4

Fig. 5

FIG. 1 is a side elevational view of a reflective bicycle pedal showing my new design, the opposite side being a mirror image thereof;

FIG. 2 is a top plan view thereof, the bottom being a mirror image of the top shown herein;

FIG. 3 is an end elevational view thereof;

FIG. 4 is an isometric view thereof; and

FIG. 5 is an end elevational view thereof opposite to that shown in FIG. 3.

I claim:

The ornamental design for a reflective bicycle pedal, as shown.
